UNITED STATES PATENT OFFICE.

JOSEPH SCHNEIBLE, OF CHICAGO, ILLINOIS.

CENTRIFUGAL FORCE-PUMP.

1,065,731.

Specification of Letters Patent. Patented June 24, 1913.

Application filed May 31, 1912. Serial No. 700,640.

To all whom it may concern:

Be it known that I, JOSEPH SCHNEIBLE, a citizen of the United States, residing at Chicago, in the county of Cook and State 5 of Illinois, have invented a new and useful Improvement in Centrifugal Force-Pumps, of which the following is a specification.

My invention relates to an improvement in the centrifugal type of pumps; and its 10 primary object is to provide a construction which shall increase the effective range of capacity and heads of centrifugal pumps while operating under varying conditions of 15 quantity and pressure, thus adapting the pump to deliver a given quantity of fluid against extraordinarily-high counter-pressure with the minimum consumption of power.

In the accompanying drawings, Figure 1 20 shows my improved pump by a view in sectional elevation, the section being taken on line 1, Fig. 3; Fig. 2 is an enlarged broken detail view of the port-forming ends of two inner wall-sections; Fig. 3 is a section on 25 line 3, Fig. 1, showing an impeller-blade tip in section, and Fig. 4 is a view similar to Fig. 3, but showing a port reducing-ring adjunct.

Like other pumps of this type, the 30 present pump comprises, in its general construction, a casing 5 having an inner annular wall 6 containing ports 7 at intervals and forming in the casing an outer delivery-chamber 8 leading to a discharge-nozzle 9, 35 and an inner pumping-chamber 10 having a central inlet 11 (shown dotted in Fig. 1) in one side of the casing, and a rotary impeller 12 on a shaft 13 journaled centrally in the opposite side of the casing for driving the impeller to revolve the fluid within 40 the pumping-chamber.

The present improvement lies, primarily, in the relation to be observed, for accomplishing the aforesaid object, of the inner 45 lines of the circumferential wall to the lines of the walls of the discharge-ports 7, formed in said wall, and the impeller-axis; and it is, furthermore, important to observe a certain height of the discharge-ports leading 50 tangentially from the pumping-chamber into the delivery-chamber, as also a particular curve of that part of the impeller-blade tip 14 which revolves in the "absolute path" of the fluid being pumped, meaning

the path which is formed by the quantity 55 of fluid discharged through each port by the action of an impeller-blade in each revolution of the impeller. To that end, the annular wall 6 is composed of a plurality of equal sections, 15, 16 and 17, of which 60 three are shown, though there may be more or fewer. Each section is formed with a "shearing" edge 18 at one end, these ends being all equidistant from the true center of the inner pumping-chamber, so that they 65 would be on a circle, indicated at v , struck from that center. From this shearing edge to a point x toward the opposite end of each wall-section, its inner surface describes an arc of a circle eccentric to the aforesaid 70 center. Thus, that extent of the inner surface of the section 15 describes an arc of a circle having the point 15' as its center, and the corresponding extents of the inner surfaces of the sections 16 and 17 describe arcs 75 of similar circles having, respectively, the points 16' and 17' as their centers.

Each discharge-port 7 is formed between adjacent overlapping ends of successive wall-sections by extending the inner surface 80 of each from the point x as a tangent, and preferably as a true tangent, to the respective arc to form the outer or upper port-wall 19, and the opposite port-wall 20 forms a throat at 21 and extends therefrom 85 outwardly, to expand the port, on a line forming with the line of the wall 19 the sides of an angle diverging substantially at 5 degrees. In other words, the discharge-ports, from the throat outwardly 90 widen on an angle of substantially 5 degrees until the velocity of the fluid is suitably reduced, according to the physical condition of different fluids to be pumped; the height and width of each discharge-port at the 95 throat 21 being such as to permit, when pumping at the maximum capacity of the pump, a velocity of the fluid pumped through it substantially equal to the rim velocity of the fluid revolving in the pumping-chamber under the action of the rotary impeller, having its blades formed with the curved tips 14. It is of advantage to form that part of the blade-tip which revolves in the absolute discharge-path of the fluid on 100 a curve, the tangent of which forms an angle of substantially five degrees with the tangent at the periphery of the impeller, as

shown. The inlet-end of each port is shown to be widened inwardly from the throat 21 to form an entrance-chamber between the shearing-edge and throat for the purpose of accumulating the fluid at the throat and thereby increasing the velocity of its passage through the latter for augmenting, by such increased velocity, the pressure in the discharge-chamber. Observance of the angle of substantially 5° on the port-inlet and impeller-tip affords the advantage of causing each tip, in passing the inlet-end of a port (which is of the venturi type) to coöperate therewith to exert, as it were, a compression-action against the revolving fluid being sheared off, thereby making it possible to discharge the latter through the ports at a pressure greater than that accepted in the art as the maximum discharging pressure. By observance of that angle in the discharge-port, the velocity at which the fluid leaves the port is converted into pressure without pulsation or back action, which would cause shock within the pumping chamber.

In the present construction, the sections of the wall 6 present an inner circular wall-surface of the diameter of a circle described from the true center of the pumping-chamber on the shearing-points 18 plus substantially the discharge-port height; the tip of an impeller-blade, in passing from port to port along the arcs forming the inner wall-surface, does not recede from the latter farther than a distance equal to or approximating the height of the ports, and such recession proceeds gradually and uniformly from shearing-edge to shearing-edge.

The number of the ports, and therefore of the wall-sections forming them, is determined by the physical condition of the fluid, fewer being required for the more viscous and a larger number for the more mobile fluids. In the same way, the number of impeller-blades or tips is determined by the physical condition of the fluid to be pumped; and in the case of a compressible fluid, these tips may be as close together as practicable without impeding the radial outward movement of the fluid through the ports. The height of the ports at the throat determines the absolute discharge-path of the fluid capable of being discharged through each port and at substantially the rim-velocity at which the fluid issues from the impeller, so that each port, when the pump is operating at its greatest capacity, discharges, at substantially rim-velocity, a stream of fluid sheared, as it were, from the rim of the revolving body of fluid at that point, and of the height and width of the port duly allowing for slippage, particularly when the pump is operating at high efficiency. With the impeller-tips, in the present construction, revolving in close prox-

imity to the shearing-edges 18 of the ports, the slippage at these points is reduced to the minimum.

When it is desired, as it sometimes is, to reduce in the present construction of pump the quantity of fluid discharged under given conditions, this may be accomplished by reducing the width of the ports 7 through the medium of a reducing-ring 22, shown in Fig. 4, instead of providing an entirely new pump with its ports of the desired width. This ring, of proper thickness, is secured, as by countersunk screws 23, at intervals, to the inner face of a head 24 of the casing, toward which it tapers, as shown at 25, from its junction with the wall 6. To accommodate the thickness of the ring the sections of the wall 6 are cut away at their sides against which the ring is fitted to the extent of the width of the latter, and the impeller-blades are cut away, on an angle, as indicated at 25', to correspond to the taper 25.

I realize that considerable variation is possible in the details of construction thus specifically shown and described, and I do not intend by illustrating a single specific, or preferred form to limit my invention thereto; my intention being in the following claims to claim protection upon all the novelty there may be in the device as broadly as the state of the art will warrant.

What I claim as new and desire to secure by Letters Patent is—

1. A centrifugal pump having in its casing an annular wall forming the inner pumping-chamber and outer delivery-chamber, said wall being in sections overlapping each other at their ends and forming ports with shearing-edges at corresponding ends of the sections on a circle having as its center that of the pumping-chamber, throats and entrance-chambers thereto expanding inwardly from the throats, the inner surface of each wall section extending from the shearing-edge end thereof as an arc of a circle eccentric to said first-named circle, and from the opposite end of the arc substantially at a tangent thereto and forming the outer port-wall.

2. A centrifugal pump having in its casing an annular wall forming the inner pumping-chamber and outer delivery-chamber, said wall being in sections overlapping each other at their ends and forming ports with shearing edges at corresponding ends of the sections on a circle having as its center that of the pumping-chamber, throats and entrance-chambers thereto expanding inwardly from the throats, the inner surface of each wall-section extending from the shearing-edge end thereof as an arc of a circle to the outer port-wall, said port-wall extending substantially at a tangent to said arc, and the diameter of said last-named

circle being that of the circle having said center plus substantially the discharge-port height.

3. In a centrifugal pump having a casing provided with an inner annular wall containing ports at intervals and forming the inner pumping-chamber and outer delivery-chamber, and a rotary bladed impeller in

the pumping-chamber, a port-width reducing-ring interposed between a side of the impeller and annular wall and the adjacent casing-head.

JOSEPH SCHNEIBLE.
